ORDNANCE MOUNT AND SUPPORTING STRUCTURE THEREFOR

Ernest F. Campbell, Springfield, Va., assignor to the
United States of America as represented by the Secre-
tary of the Navy

Filed Apr. 26, 1956, Ser. No. 580,969

4 Claims. (Cl. 89—37)

(Granted under Title 35, U.S. Code (1952), sec. 266)

The invention described herein may be manufactured and used by or for the Government of the United States of America for governmental purposes without the payment of any royalties thereon or therefor.

The present invention relates to ordnance mounts and supporting structures therefor, and more particularly to an ordnance mount which is supported by vertically spaced platforms.

While the invention is primarily intended for the installation of ordnance devices on marine vessels, as disclosed herein, it is to be understood that it is also readily adaptable for use in shore based ordnance installations.

In the past, it has been the practice to mount and support naval ordnance devices such as guns, missile launchers, and the like, on but a single deck or platform of a vessel, usually the top deck sometimes referred to as the gun deck or weather deck. In this arrangement substantially all of the forces and overturning moments caused by operation of the device, and from the motion of the vessel, are imparted to the single deck structure in the form of vertical forces or forces normal to the plane of the deck. In order to securely support the ordnance device on the single deck it was necessary to mount the device on a large heavy trunk or base member and, in addition, to add heavy reinforcing elements to the normal deck structure adjacent and surrounding the trunk or base member. This type of installation or single deck mounting arrangement has certain inherent disadvantages in that the large base member together with the reinforcing elements not only add considerable weight to the vessel, which is in and of itself undesirable, but the weight being located in the extreme upper portion of the vessel raised the center of gravity of the vessel. Such effect on the center of gravity is particularly critical in smaller ships. Further, the single deck method of mounting also requires unusually large bearing assemblies for rotatably supporting the large circumferenced base or trunks, and these bearings are expensive and difficult to manufacture within prescribed tolerances.

The present invention overcomes the foregoing disadvantages in that it provides an ordnance mount which is supported by two or more spaced decks or platforms whereby the forces or overturning moments caused by operation of the ordnance device and/or by the vessel's motion will be resisted by reactions developed in the planes of the two decks or platforms.

Since the conventional platform or deck structures are capable of sustaining considerably greater axial forces than forces applied normal to their surfaces the two-deck mount can be made of lighter construction with a relatively small circumferenced base member, and additional reinforcing structures may be kept at a minimum. Also, the various bearing assemblies, both radial and thrust, may be reduced in size to a point where they may be easily and economically manufactured. Additionally, since the total weight of the two-deck mounting is substantially less than the total weight of a conventional single deck mounting for any given ordnance device, and inasmuch as the center of the weight of the former is located at a lower point within the vessel, the improved two-deck system of mounting has less adverse effect on the vessel both as to the addition of weight thereon and

2

also as to the raising of the center of gravity, each of which are critical factors as far as ship construction is concerned.

As an example of the weight saving feature the total weight of a high velocity naval gun in present service utilizing the conventional single deck mounting is 120,000 pounds as compared to a calculated total weight of approximately 75,000 pounds should the same gun be mounted by the proposed two-deck arrangement.

Accordingly, it is an object of the present invention to provide a new and improved lightweight ordnance mount and installation therefor.

Another object of the invention is to provide an ordnance mount of minimum weight which is capable of supporting ordnance of maximum fire power.

A still further object of the invention is the provision of an ordnance mount and supporting structure therefor wherein substantially all of the forces induced in the mount will be transmitted into the supporting structure in an axial direction.

An additional object of the present invention is to provide a lightweight ordnance mount which may be readily incorporated within a vessel with a minimum amount of reinforcing or modification to the normal ship's structure.

Yet, a further object of the invention is to provide a relatively lightweight ordnance mount which is adapted to be rotatably supported within a vessel's structure, said mount being so disposed within the vessel that its additional weight has a minimum effect on the center of gravity of the vessel.

A still further objective of the present invention is that of providing a relatively lightweight ordnance mount for supporting ordnance devices on marine vessels, said mount being rotatably supported within vertically spaced decks of said vessel such that substantially all of the overturning forces caused by operation of the ordnance device and movement of the vessel will be transmitted to, and accepted by, adjacent vessel structure in planes parallel to the decks.

Other objects and many of the attendant advantages of this invention will be readily appreciated as the same becomes better understood by reference to the following detailed description when considered in connection with the accompanying drawings wherein:

FIG. 1 is a front elevational view, partly in section, of one embodiment of the improved ordnance mount;

FIG. 2 is an enlarged vertical sectional view taken along lines 2—2 of FIG. 1 looking in the direction of the arrows;

FIG. 3 is an enlarged vertical sectional view taken along lines 3—3 of FIG. 1 looking in the direction of the arrows; and

FIGS. 4 and 5 are schematic side elevational views showing respectively, the general disposition of forces in the two-deck mounting arrangement of the present invention and those in the conventional single deck mount.

Referring now to the drawings, wherein like numerals designate like or corresponding parts, there is shown in FIG. 1 an ordnance mount generally designated by the numeral 10 rotatably supported by a top deck or platform 11 and a lower deck or platform 12. The mount comprises an elongated central column or trunk member 13 which is adapted to support ordnance devices such as guns, missile launchers, or the like at its upper end together with conventional trunnion bearing assembly and power means for moving the devices in elevation. In the instant embodiment the mount is illustrated as supporting a twin barreled gun 14 by means of trunnion or elevation bearings 15. The central column or trunk 13 is preferably hollow to accommodate therein conventional hoist means (not shown) for conveying projectiles or missiles up to the respective ordnance devices. The cross-sectional de-

sign of the column or trunk may be cylindrical or rectangular, but it is generally the latter since this design lends itself more readily to receiving auxiliary equipment therein.

As shown in FIGS. 1 and 2 column 13 extends through a circular aperture 16 in the upper deck 11 with the lower end of the column extending into well or aperture 17 of the lower deck 12. A skirt-like trunk or column member bearing support 18 including a pair of radially disposed mutually spaced plates having an outer circular peripheral edge member 19 carried thereby and secured to the column member at a point intermediate its length such that the peripheral edge member 19 is in radially spaced adjacent relationship with the inner edge of the aperture 16. An annular deck ring or outer bearing race support member 20 is mounted on the top deck surrounding the aperture 16, and includes a lower flange member 21 for supporting a training circle 22 and an upper flange member 23 having a seat 24 provided therein for receiving the outer race 25 of the frictionless floating radial bearing assembly 26. The inner bearing race 27 of the bearing assembly 26 is supported in recess 28 of a bearing ring 29 attached to the periphery of the trunk bearing support plate 18. While the radial bearing assembly shown is of the roller type employing rollers 30 it is to be understood that a suitable ball type radial bearing could be utilized in lieu thereof. The inner and outer bearing races 27, 25 are retained in place by clamp or retainer members 31 and 31a. Projecting radially outwardly from the trunk bearing support plate 18, and above the bearing assembly 26 is a circular disc-like weather shield 32 which cooperates with stationary sealing means 33 attached to the upper deck to protect the assembly against the entry of water and foreign elements.

Attached to the outside of the lower portion of the central column or trunk 13 is a train drive mechanism which comprises motor 34, the gear train 35, and training pinion 36, having teeth 37 which engage the teeth 38 on the inner face of the training circle 22. When the train drive mechanism is in operation the training pinion 36 is caused to rotate, thus advancing the trunk or column around in a circular direction to train the mount.

As illustrated in FIG. 3 the central column 13 has a reduced spindle member 39 secured to the lower end which is rotatably supported in the well or aperture 17 in the lower deck or platform 12 by means of thrust bearing assembly 40 and a combination radial-thrust bearing 41. A base and bearing housing 42 disposed within the well 17 of the lower deck 12 surrounds the spindle 39 and contains dividing means in the form of an inwardly projecting shoulder 43 to form in cooperation with the reduced portion of the spindle an upper bearing receiving chamber 44 for receiving and retaining the thrust bearing assembly 40, and a lower chamber 45 for receiving and retaining the radial-thrust bearing assembly 41. The thrust bearing assembly 40 comprises suitable rolling elements such as rollers 46 positioned between an upper race 47 and a lower race 48, the lower race 48 being seated on the top of the inwardly projecting shoulder 43 of the base and bearing housing 42, and the upper race 47 being positioned against the base 49 of the reduced portion of the spindle 39.

The radial-thrust bearing assembly 41 includes inclined rollers 50, an outer race 51 positioned against the underside of the inwardly projecting shoulder 43 and an inner race 52 seated against the lower portion of the spindle and retained in place by retaining nut 53 threaded on the lower threaded portion of the spindle 39. Conventional sealing means 54 are provided between the top of the base and bearing housing and the upper portion of the spindle of the column or trunk member, and between a lower extension member 55 of the base and bearing housing and the lower extremity of the spindle.

It will thus be seen that the ordnance mount 10 is rotatably supported for training movement in the two decks

by virtue of the radial bearing 26, thrust bearing 40, and radial-thrust bearing assembly 41, and that such training movement is controlled by the train drive mechanism previously described. Hence, when overturning forces, indicated by arrow OF in FIG. 4, are imparted to the two-deck mount 10 by operation or firing of the ordnance device 56 or through movement of the vessel, substantially all of these forces will be transmitted into the deck structure in the form of axial or horizontal forces F, which in turn will be resisted by means of a reaction couple (not indicated). It has been found that the horizontal reaction at the lower deck is approximately one half the magnitude of the horizontal reaction in the upper or top deck. Any vertical forces VF acting in an upwardly direction will be of a relatively small amount as compared to the horizontal forces F, and will be resisted mainly by the radial-thrust bearing assembly. It is important to note that substantially all of the overturning moments or forces have been converted into horizontal forces or forces parallel to the planes of the decks which forces are of the type that can be more easily sustained by normal deck structure without excessive reinforcement.

Under similar firing or operational conditions it will be seen from reference to FIG. 5 that the same overturning forces OF imparted to the conventional single deck mount 57 will result in forces F and opposing reactions (not indicated) which are normal to the single deck structure. These vertical or normal forces and the accompanying twisting or torque effect on the deck are considerable and since the normal deck structure cannot alone sustain these forces in any great degree substantial reinforcement is required.

Although the embodiment of the invention disclosed herein is particularly directed to the installation of ordnance mounts on marine vessels, it is obvious that it may readily be adapted for use in land base ordnance installations for the mounting of ordnance devices such as guns or missile launchers on mobile or stationary mounts.

Obviously many modifications and variations of the present invention are possible in the light of the above teachings. It is therefore to be understood that within the scope of the appended claims the invention may be practiced otherwise than as specifically described.

What is claimed is:

1. An ordnance mount comprising; a longitudinally disposed rotatable column member adapted to support an ordnance device at one end thereof for rotation, a first deck having an aperture therein, a second deck disposed beneath said first deck, a bearing support mounted on the column member and provided with a pair of radially disposed mutually spaced circular plates carried by said column member intermediate the ends thereof and in alignment with said aperture and in spaced relationship with said first deck, said support having a circular peripheral edge member secured to the peripheral edges of said plates, a spindle secured to the other end of said column member, a deck ring secured to said first deck adjacent said aperture and having a downwardly extending flange integrally formed therewith and disposed within said aperture and an upwardly extending flange integrally formed therewith in spaced relationship with said edge member, radial bearing means disposed between said edge member and said upwardly extending flange for rotatably supporting said column member on said first deck, a bearing housing secured to said second deck and enclosing said spindle, a pair of roller bearings disposed within said housing between the housing and the spindle for rotatably supporting the column member on said second deck, a training circle secured to said downwardly extending flange on said deck ring and disposed within said aperture, a training pinion rotatably supported on said circular plates in engagement with said training circle and rotated with respect thereto for rotating said column member, and power means carried by said column

member and operatively connected to said training pinion for driving said pinion.

2. A mount in accordance with claim 1 and further including means carried by said housing in engagement with said spindle and column member for sealing said bearings within said housing.

3. A mount in accordance with claim 1 and further including a circular shield carried by said circular peripheral edge member and extending radially outwardly therefrom a substantial distance beyond said annular plate, radial bearing means and aperture and disposed thereabove, means carried by said first deck in sealing engagement with said circular shield for providing a watertight seal therebetween.

4. An ordnance mount comprising, a longitudinal column member adapted to support an ordnance device at its upper end, a first deck, a second deck, said first deck being positioned above said second deck in spaced substantially parallel relationship therewith and having a circular aperture formed therethrough, a radially extending bearing support including a pair of mutually spaced circular plates disposed within said aperture and carried by the column member intermediate its ends, an annular member secured to the peripheral edges of said pair of plates, a spindle secured to the lowermost end of the column member, a deck ring secured to said first deck and having a pair of annular flanges integrally formed therewith, one of said pair of flanges being disposed within said aperture and extending downwardly from said deck ring, the other one of said pair of flanges being in mutually spaced relation with respect to said one flange and extending upwardly from the deck ring, said column

member being disposed in normal relationship to the decks and extending through said aperture and positioned such that the annular member of the bearing support is adjacent to and in radial spaced relationship from the edge of the aperture and said spindle is in spaced adjacent relationship with the second deck, radial bearing means interposed between said annular member and said upwardly extending flange, a bearing housing mounted on said second deck and enclosing the spindle in spaced relationship with respect thereto, a thrust bearing disposed in one end of said housing and positioned between the housing and spindle, a radial-thrust bearing disposed in the other end of said housing and positioned between the housing and spindle, a training circle having teeth on the inner surface thereof and secured to said downwardly extending flange in adjacent encircling relationship with said aperture, power means carried by the column member, and a training pinion rotatably mounted on said support in engagement with said teeth on the training circle for imparting rotary movement to said column member as said pinion is rotated by said power means.
